UNITED STATES PATENT OFFICE.

CECIL R. ARNOTT, OF SPOKANE, WASHINGTON.

SAFETY APPLIANCE FOR ELEVATORS.

1,176,189.

Specification of Letters Patent. Patented Mar. 21, 1916.

Application filed June 2, 1915. Serial No. 31,753.

To all whom it may concern:

Be it known that I, CECIL R. ARNOTT, a citizen of the United States, residing at Spokane, in the county of Spokane and State of Washington, have invented certain new and useful Improvements in Safety Appliances for Elevators, of which the following is a specification.

My invention relates to improvements in safety appliances for elevators, adapted to prevent the operation of the starting mechanism therefor, when one or more of the doors of the elevator shaft is partly or wholly open.

An important object of the invention is to provide apparatus of the above mentioned character, which is simple in construction, inexpensive to manufacture, strong and durable.

Other objects and advantages of the invention will be apparent during the course of the following description.

In the accompanying drawings forming a part of this specification and in which like numerals are employed to designate like parts throughout the same, Figure 1 is a side elevation of apparatus embodying the invention, Fig. 2 is a similar view taken at a right angle to Fig. 1, Fig. 3 is a diagrammatic view of the riders and associated elements, Fig. 4 is a horizontal sectional view taken on line 4—4 of Fig. 1, Fig. 5 is a perspective view of the rider, and, Fig. 6 is a horizontal sectional view through one corner post taken above a guide member.

In the drawings, wherein for the purpose of illustration is shown a preferred embodiment of my invention, the numeral 5 designates corner posts of an elevator shaft, 40 which are vertically arranged and held stationary by any suitable means. An elevator (not shown) is mounted to move vertically within the shaft, as is customary.

The elevator shaft may be of any height and have two or more landings 6, as shown. The opposite sides of the elevator shaft, at each landing, are formed open, and receive vertically sliding doors or gates 7, while the other sides of the elevator shaft

50 are closed, as shown at 7'. These doors or gates 7 are slidably mounted between strips 8', secured to the posts 5 as shown in Fig. 4.

Arranged preferably exteriorly of each door or gate 7 is a rider designated as a whole by the numeral 8. This rider comprises a horizontal arm 9, carrying an inverted U-shaped head 10, which straddles the upper end of the door or gate 7, but has no attachment thereto. Connected with the horizontal arm 9 is a diagonal brace 60 arm 11, extending downwardly therebelow. The arms 9 and 11 are rigidly connected with a pair of vertical longitudinally movable rods 12, which are rigidly connected at their ends, as shown at 12'. These rods 65 12 are mounted to slide in guides 13 (see Fig. 6), rigidly attached to the posts 5. It is thus apparent that the rider will move up with its door or gate 7, when the door or gate is elevated, and the rider may be 70 elevated while the door or gate remains in the closed position.

There are two pairs of the vertical rods 12, as is obvious, and means are provided to connect them, whereby when one pair is 75 elevated or lowered a corresponding movement of the other pair is effected. This means comprises cables 14 or the like. Each cable 14 is attached to one horizontal arm 9 and extends upwardly and passes about 80 pulleys 15, and downwardly beneath a pulley 16. The cable then extends upwardly for connection with one diagonal brace arm 11 in the other rider, in the uppermost pair. It is obvious that when the rod 12, to the 85 left, in Fig. 3, is elevated, the outer cable 14 is moved downwardly, in the direction of the arrow, and pulls the rod 12 to the right upwardly, while the upward movement of the rod 12 to the right pulls the 90 inner cable 14 downwardly, as the other rod is elevated. The pulleys 15 and 16 are suitably connected with the frame work of the elevator shaft or other supports.

While I prefer to use pairs of rods 12, 95 on account of the strength and lightness of the construction, yet it is obvious that satisfactory results are obtainable by using a single rod in place of each pair, and such change is considered as within the spirit 100 of the invention.

The starting mechanism of the elevator comprises a grooved wheel 17, rotatably mounted upon a stationary shaft 18, ar-

ranged adjacent the lowermost landing 6. This grooved pulley is engaged by the usual cable or rope 19, extending longitudinally through the shaft, with one portion thereof 5 extending through the elevator. The grooved pulley 18 has a toothed wheel or pinion 20 secured to one side thereof and preferably cast integral therewith. This pinion is adapted to be engaged by a bolt 10 or lock member, mounted to reciprocate within a tubular casing 22, rigidly mounted upon a stationary bracket 23. This bolt has connection with a retractile coil spring 23', surrounding it, and having its lower 15 end connected with the lower end of the tubular casing. The function of this spring is to move the bolt downwardly into engagement with the pinion, when it is released.

20 Pivots connected with the upper end of the bolt 21 is a vertically swinging lever 24, pivoted between its ends as shown at 25. The outer end of the lever 24 is provided with a slot 26, receiving a pivot element or pin 27, which is rigidly secured to the lower end of one pair of vertically movable rods 12.

The operation of the apparatus is as follows: When the elevator is stopped at the 30 desired landing, the door or gate 7 at such landing, is raised to the open position. When this door is elevated the corresponding rider 8 moves up, whereby the rod or pairs of rods 12 attached thereto is elevated. 35 This movement of the pair of rods 12, carries the other rider or riders connected therewith upwardly, and the other pair of rods 12 and riders secured thereto are also simultaneously elevated, as hereinabove explained. It is obvious that when any one 40 of the doors or gates is elevated, both pairs of rods 12 and their riders are raised. Upon the upward movement of these pairs of rods 12, the outer end of the lever 24 is swung 45 upwardly and its inner end downwardly, whereby the spring 23' moves the bolt 21 downwardly into engagement with the pinion 20 and the starting mechanism is locked against movement. It will then be impossible 50 to start the elevator until all of the gates are returned to the lower closed position.

It is to be understood that the form of my invention herewith shown and described 55 is to be taken as a preferred example of the same, and that various changes in the shape, size, and arrangement of parts may be resorted to without departing from the spirit of the invention or the scope of the subjoined claims.

Having thus described the invention, I claim:

1. Safety apparatus for elevators, comprising a plurality of sets of riders adapted 65 to contact with vertically movable doors to

move therewith and with relation thereto, means connecting the riders in one set with the riders in the other set so that they move together in the same direction upon the movement of one rider in one direction, and means operated upon the movement of the riders in one direction to lock the elevator starting mechanism against movement. 70

2. Safety apparatus for elevators, comprising a plurality of vertically movable 75 rods adapted to be arranged upon opposite sides of the elevator shaft, means connecting the rods whereby they move together in the same direction, a plurality of riders connected with each rod and adapted to contact with vertically movable doors of the elevator shaft, and means operated upon the upward movement of one rod to lock the elevator starting mechanism against movement. 80

3. Safety apparatus for elevators, comprising a plurality of vertically movable rods to be arranged upon opposite sides of the elevator shafts; sets of upper and lower pulleys arranged near the upper ends of the rods; cables connecting the upper ends of the rods, each cable having one end connected with the adjacent rod and passed upwardly about the upper set of pulleys and downwardly beneath the lower pulley adjacent the other rod and upwardly for connection with the other rod; a plurality of riders carried by each rod and adapted to contact with vertically movable doors of the elevator shaft; and means operated upon the upward movement of one rod to lock the elevator starting means against movement. 90

4. Safety apparatus for elevators, comprising a plurality of vertically movable rods adapted to be arranged upon opposite 105 sides of the elevator shaft, pulleys arranged near the upper ends of the rods, cables connecting the upper ends of the rods and engaging the pulleys in a manner whereby when either rod is elevated the other rod moves upwardly with it, a plurality of riders carried by each rod and adapted to contact with vertically movable doors of the elevator shaft, a swinging lever pivotally connected with one vertically movable rod, 110 a pinion for controlling the operation of the elevator starting mechanism, and a bolt movable into and out of engagement with the pinion to control its rotation and connected with the lever. 115

5. Safety apparatus for elevators, comprising a plurality of vertically movable rods adapted to be arranged upon different sides of the elevator shaft, pulleys arranged near the upper ends of the rods, cables connecting the upper ends of the rods and engaging the pulleys in a manner whereby when either rod is elevated the other rod moves up with it, a plurality of riders carried by each rod and adapted to contact 125 130

with vertically movable doors of the elevator shaft, a swinging lever pivotally connected with one vertically movable rod, a pinion for controlling the operation of the elevator starting mechanism, a bolt connected with the lever and adapted to engage and disengage the pinion, a sleeve within which the bolt operates, and a spring arranged

within the sleeve to move the bolt downwardly.

In testimony whereof I affix my signature in presence of two witnesses.

CECIL R. ARNOTT.
